UNITED STATES PATENT OFFICE

2,575,319

HYDRAULIC TRANSMITTER

Robert Stevenson, Barrington, R. I., assignor to
Merit Engineering, Inc., a corporation of Rhode
Island

Application June 17, 1946, Serial No. 677,371

1 Claim. (Cl. 60—54.6)

1

This invention relates to a hydraulic control system and more particularly to the hydraulic transmitter for the system.

In the transmitting of liquid for the hydraulic control of movable parts, the pressure in the transmitter has been rather critical and if the fluid was not exactly properly proportioned to the hand operated lever, considerable pressures were developed, making the hand operation of the system difficult.

One of the objects of this invention is to provide an arrangement so that the same amount of pressure will be present in the hydraulic system at all times and the movement of the handle for manipulating the liquid in the system will be uniform.

Another object of the invention is to provide a system in which there may be expansion of the liquid used without affecting the operation of the system.

Another object of the invention is to provide an expansion chamber in the operating system upon which a constant pressure is provided and which will permit of considerable change in volume of the liquid utilized without materially changing the pressure in the system.

Another object of the invention is to utilize the expansion chamber to some extent to supply any losses of liquid in the system which may be small so that the system will continue to function with varying volumes of liquid therein at substantially the same resistance to hand pressure.

With these and other objects in view, the invention consists of certain novel features of construction, as will be more fully described and particularly pointed out in the appended claim.

In the accompanying drawings:

Fig. 1 is a front elevation illustrating the device;

Fig. 2 is a side elevation thereof;

Fig. 3 is a sectional view through substantially the center of the operating parts of the transmitter;

Fig. 4 is a top plan view of the structures illustrated in Figs. 1 and 2.

The complete system in which this invention is used is illustrated in my co-pending application, Ser. No. 541,449, now abandoned, in which I have illustrated a transmitter unit in the lower part of Fig. 1. This transmitter unit consists of cylinders in which pistons are mechanically moved by hand pressure in reverse relation so that if one piston is moved downwardly, the other piston is moved upwardly so as to transmit liquid along

certain conduits to apply pressure to some operating parts at a distance. Each of these flow lines is a complete system in itself and I have provided an expansion chamber which communicates with each of the flow lines at a point where the communication will not be cut off by the piston so that the system is maintained under substantially the pressure of a spring in the expansion chamber which pressure is sufficient to move the operating parts which the transmitter controls.

With reference to the drawings, 10 designates generally a block which is provided with a plurality of bores, there being the bores 11 and 12 located in close adjacency which open into larger threaded bores 13 and 14 which are closed by plugs 15 and 16 having conduits 17 and 18 therein which are used for the transmission of liquid to the point of use. Pistons 19 and 20 are slideable in the bores 11 and 12, each having stems 21 and 22 extending out of the bores at their opposite ends for the reception of operating pressures. Springs 23 and 24 surround the stems 21 and 22 and serve as a cushion for the movement of the pistons to project the stems out of the bores at one end thereof. Vent holes 25 and 26 are provided to prevent trapping of air beneath the pistons.

The body 10 has a pair of arms 27 and 28 which extend upwardly therefrom and which serve to rotatably hold a shaft 29. The shaft has cams 30 and 31 mounted thereon in a plane so as to engage the ends of the stems 21 and 22. A handle 30' having a knob 31' extends laterally from the shaft 29 and this handle engages a stop 32 on one side and a stop 33 on the other side so as to provide a movement of the shaft through substantially 180 degrees. The cams 30 and 31 are oppositely arranged so that as the cam 30 forces the stem 21 and piston 19 downwardly in the chamber 11, the cam 31 is raised so as to permit the stem 22 and piston 20 to move upwardly in the chamber 12 by the action of the reverse flow of fluid in the system. Each flow line is maintained full of liquid and the liquid is moved in one direction, as above described, by the pistons 19 and 20 and in the reverse direction by the work acted upon when either of the pistons are released from engagement with the cams 30 and 31. The work controlled may be a plurality of valves as set forth in my co-pending application, above referred to.

In order to provide an expansion chamber, I have provided bores 34 and 35 in the body 10 which have plungers 36 and 37 slidably mounted

therein. The upper ends of these bores are enlarged and threaded as at 38 and 39 for the reception of caps 40 and 41 which provide a long container for springs 42 and 43 which have abutment and closure means 44 and 45 at the upper end of these caps. These caps are reduced and threaded at their lower ends to engage the threads 38 and 39. In order to provide communication between these chambers 34 and 35, I have provided conduits 46 and 47 which extend to the junction between the cylinders 11 and 12 and conduits 17 and 18. These conduits 46 and 47 are usually provided by bores from the sides of the body and are closed by headed screws 50 and 51 at the ends of these bores.

The tension of the springs 42 and 43 determines the pressure which will exist in each of the systems. Should expansion occur these springs may be somewhat compressed but will remain at substantially the same pressure. Should contraction occur or leakage occur in the system, the springs will force the plungers downwardly so that substantially the same pressure is maintained. Thus the resistance to the movement of the handle on the pistons 19 and 20 which moves the cams will be maintained substantially the same and liquid will be transmitted along the conduits 17 as the piston 19 is moved downwardly while as the cam 31 is moved to free the piston 20 the fluid will flow in the other direction to push the piston 20 upwardly and follow the cam surface until stopped by the spring 24.

I claim:

A hydraulic transmitter comprising a solid block having a pair of cylindrical bores each closed at one end by a wall of the block, closure means including a transmission conduit at the other end of each bore, a piston in each bore having a stem extending axially out of the bore through the said wall of the block, a spring in each bore encircling each stem and acting between said wall and pis-

ton to urge the piston in one direction, a shaft in the plane of said stems extending laterally of the axes of said stems, a pair of similar cams fixed on said shaft so that when the surface of one moves toward one stem the surface of the other moves away from the other stem, a handle on said shaft and stops limiting movement of said handle in opposite directions through 180 degrees, said block also having a pair of expansion chambers therein, one bore being connected in all positions of the piston therein with one chamber and the other bore being connected in all positions of the piston therein with the other chamber, a plunger in each chamber and a spring acting on each plunger to exert a pressure on the liquid in the chamber, bore and conduit system to maintain a substantially constant pressure therein.
